BLADE SHARPENING DEVICE

Herman L. Holland and Harold A. Klatt, Clear Lake, Iowa, assignors to Klaho Manufacturing Company, Inc., Clear Lake, Iowa

Filed Nov. 7, 1957, Ser. No. 695,036

6 Claims. (Cl. 51—210)

Our invention relates to a sharpening tool and more particularly to a sharpening tool that can be powered by a conventional electric hand drill.

Blade sharpening units are generally very old in the art but these devices known to us have certain serious shortcomings. The greatest shortcoming of these devices is that they cannot be used upon a blade unless the blade is conveniently placed in a vice or clamp at a location where the operator has free and easy access to the blade. A further shortcoming of the sharpening units known to us is that they must all be operated with both hands even if their power is derived from manual, mechanical or electrical means. All of the mechanical or electrically powered devices are equipped with their own individual power units which adds not only to their cost but also to their difficulty in handling and operating. Furthermore, many of these devices are dangerous instrumentalities when used in the hands of the unskilled.

Therefore, the principal object of our invention is to provide a blade sharpening device that can easily perform its function, despite the position of the blade.

A further object of our invention is to provide a blade sharpening device that can be successfully operated with the use of one hand.

A further object of our invention is to provide a blade sharpening device that can maintain a constant angle of attack on the blade.

A still further object of our invention is to provide a blade sharpening device that can be powered by a conventional hand electric drill.

A still further object of our invention is to provide a blade sharpening device that will protect the operator from the sharpened blade during the sharpening operation.

A still further object of our invention is to provide a blade sharpening device that is economical of manufacture, durable in use, and refined in appearance.

These and other objects will be apparent to those skilled in the art.

Our invention consists in the construction, arrangements, and combination, of the various parts of the device, whereby the objects contemplated are attained as hereinafter more fully set forth, specifically pointed out in our claims, and illustrated in the accompanying drawings, in which:

FIG. 1 is a perspective view of our device being used on the blade of a flywheel-type forage harvester;

FIG. 2 is a rear end elevational view of our device; and

FIG. 3 is a sectional view of our device taken on line 3—3 of FIG. 2.

We have used the numeral 10 to generally designate the frame of a flywheel-type forage harvester which is partially shown in FIG. 1. A bearing member 12 is secured thereto in any convenient manner and rotatably supports shaft 14 which in turn is connected to a source of rotational power. The exact details of the forage harvester partially shown in FIG. 1 do not constitute a part of my invention and are illustrated in FIG. 1 to indicate the operating position of our device. The vertical flywheel 16 is rigidly secured to shaft 14 and a plurality of brackets (not shown) extend from the side thereof to receive bolts 18. The bolts 18 and corresponding brack-

2

ets act to hold cutting blades 20 and 22 in spaced apart parallel relation to flywheel 16.

The numeral 24 designates the power shaft of our device. The forward portion 26 of shaft 24 is slightly larger in diameter than the rearward portion 28. The forward end 29 of portion 26 is threaded with left-handed threads and the rearward end 30 of the forward portion is threaded with right-handed threads.

A lug washer 32 is rigidly secured to the center of forward portion 26 of shaft 24. A conventional wheel-type sharpening stone 34 with center hole 36 is slidably mounted on portion 26 and is of sufficient thickness to span the distance between lug washer 32 and the threaded end 29 of shaft 24. A washer 38 is conventionally placed over shaft 24 adjacent the forward side of stone 34 and nut 40 is then placed on the threaded forward end 29 of the shaft 24 to tighten washer 38 and stone 34 against lug washer 32. The center portion of the rearward face of stone 34 can be recessed at 42 to receive lug washer 32. A spacer washer 44 is rotatably mounted on shaft 24 adjacent lug washer 32. A guide 46 is rotatably mounted on the portion 26 of shaft 24 and is of sufficient thickness to substantially span the distance from spacer washer 44 to the threaded end 30 of portion 26 of shaft 24. We have shown the guide 46 to be frusto-conical in shape. This exact shape is not critical as long as the guide presents a straight surface angularly disposed to stone 34. It should be noted that the "top" or forward end of the guide 46 is adjacent spacer washer 44 and has a slightly greater diameter than the spacer washer.

A ball bearing ring can be mounted within guide 46 to reduce friction between the guide and the portion 26 of shaft 24. A recessed opening 48 is concentrically located in the rear face of guide 46 and ring 50 is rigidly secured therein. A core 52 is rotatably mounted within ring 50 and also rotatably mounted on portion 26 of shaft 24. Ball bearings 53 are thereupon located between ring 50 and core 52 to perform their conventional function. A washer 54 can be placed on portion 26 adjacent core 52 and nut 56 can be threadably placed on end 30 of portion 26 to move the guide 46 towards stone 34.

The rearward end 58 of shaft 24 can be square in cross section so as to facilitate its being rigidly secured in the chuck 60 of electric drill 62.

Ordinarily, the tapered cutting edges 64 of blades 20 and 22 can be sharpened only when the blades are removed from the flywheel 16. However, the above described structure of our device will permit the uniform sharpening of the blades 20 and 22 without removing the blades from the machine.

The end 58 of shaft 24 can be placed in the chuck 60 of drill 62. As shown in FIG. 3, the forward conical-shaped surface of guide 46 is placed against the side of cutting blade 20 which is opposite to the cutting edge 64 of the blade. The sharpening stone 34 is then brought into engagement with cutting edge 64 so that the rearward surface of the stone and the cutting edge of the blade are in the same plane. Since the top or forward end of the guide 46 is larger than spacer washer 44, and since the guide 46 is slightly spaced apart from stone 34, a very fine edge can be created on the lower edge of cutting blade 20, as shown in FIG. 3. We have found that the above arrangement of the stone 34, spacer washer 44 and guide 46 permits a much better sharpening effect on blade 20 than if the guide actually engaged the cutting stone.

As the electric drill 62 is actuated in conventional fashion, the shaft 24 and stone 34 will commence to rotate with the drive shaft of the drill. The drill and sharpening assembly are then moved back and forth along the blade parallel to the blades' longitudinal axis. Since guide 46 is rotatably secured to the portion 26 of

shaft 24, the guide will rotate with respect to the blade and will reduce the frictional effect therebetween as the drill and sharpening unit are moved back and forth. It is seen, therefore, that our device can be used to sharpen blade 20 even though the cutting edge 64 of the blade is only a very short distance from the flywheel 16.

Since portion 28 of shaft 24 is of smaller diameter than portion 26, nut 56 can be removed from the threaded end 30 of portion 26 to permit the nut and guide 46 to be slidably removed over the narrow portion 28 of the shaft. This would permit guides of different shapes to be interchanged on our device without also having to remove the cutting stone 34. Of course, stone 34 could be removed by actuating nut 40 in conventional fashion. The left-handed threads on end 29 of shaft 24 will prevent the rotation of shaft 24 from loosening nut 40 and stone 34.

Since sharpening stone 34 is detachable from shaft 24 by means of nut 40, and since guide 46 is detachable from shaft 24 by means of nut 56, the positions of the stone and guide can be interchanged. Thus, if space requirements would not permit the sharpening unit to be applied to the blade 20 as shown in FIG. 3, the stone 34 and guide 46 could be removed from the shaft 24. The shaft 24 could thereupon be turned end for end (180°), the spacer washer 44 and guide 46 placed on the forward end 29 of portion 26 to assume the same position with respect to blade 20, as shown in FIG. 3. The sharpening stone 34 could thereupon be placed on the rearward end 30 of portion 26 with recess 42 adjacent lug washer 32. This arrangement of structure would not change the position of the stone 34, spacer washer 44 or guide 46 with respect to blade 20, but it would permit shaft 24 to be operated from the left-hand side rather than the right-hand side as seen in FIG. 3.

Some changes may be made in the construction and arrangement of our blade sharpening device without departing from the real spirit and purpose of our invention, and it is our intention to cover by our claims, any modified forms of structure or use of mechanical equivalents which may be reasonably included within their scope.

We claim:

1. In a sharpening device, a shaft, a sharpening stone element rigidly secured to one end of said shaft, a guide member rotatably mounted on said shaft adjacent said sharpening stone element, said guide member having an inclined blade supporting surface adjacent the side of said sharpening stone element where said guide member is mounted on said shaft, said blade supporting surface on said guide member adapted to support a straight elongated blade, and the other end of said shaft being extended so as to permit its introduction into the chuck of a portable power tool.

2. In a sharpening device, a shaft, a wheel type sharpening stone element rigidly secured to one end of said shaft, a guide member rotatably mounted on said shaft adjacent said stone element, said guide member having a blade supporting surface adjacent the side of said stone element where said guide member is mounted on said shaft, said blade supporting surface having shape to present a straight line contact with a flat surface and to form an angle with said stone element, and the other end of said shaft being extended so as to permit its introduction into the chuck of a portable power tool.

3. In a sharpening device, a shaft, a wheel type sharpening stone element rigidly secured to one end of said shaft, a guide member rotatably mounted on said shaft

adjacent said stone element, said guide member having a blade supporting surface adjacent the side of said stone element where said guide member is mounted on said shaft, said blade supporting surface having shape to present a straight line contact with a flat surface and to form an angle with said stone element, a spacer washer on said shaft between said stone element and said guide member, and the other end of said shaft being extended so as to permit its introduction into the chuck of a portable power tool.

4. In a sharpening device, a shaft, a wheel type sharpening stone element rigidly secured to one end of said shaft, a guide member rotatably mounted on said shaft, said guide member having the shape of a frusto-cone, said guide member having a blade supporting surface adjacent the side of said stone element where said guide member is mounted on said shaft, and the other end of said shaft being extended so as to permit its introduction into the chuck of a portable power tool.
5. In a sharpening device, a shaft, a wheel type sharpening stone element rigidly secured to one end of said shaft, a guide member rotatably mounted on said shaft, said guide member having the shape of a frusto-cone with the smaller end of said guide member being adjacent said stone element, said guide member having a blade supporting surface adjacent the side of said stone element where said guide member is mounted on said shaft, a spacer washer on said shaft between said stone element and said guide member, said spacer washer having a diameter less than the diameter of the smaller end of said guide member, and the other end of said shaft being extended so as to permit its introduction into the chuck of a portable power tool.
6. In a sharpening device, a shaft, a wheel type sharpening stone element rigidly secured to one end of said shaft, a guide member rotatably mounted on said shaft adjacent said stone element, said guide member having a blade supporting surface adjacent the side of said stone element where said guide member is mounted on said shaft, said blade supporting surface having a shape to present a straight line contact with a flat surface and to form an angle with said stone element, the other end of said shaft being extended so as to permit its introduction into the chuck of a portable power tool, and means on said shaft whereby said sharpening stone element and said guide member can be selectively removed from said shaft to have their positions thereon interchanged.
